UNITED STATES PATENT OFFICE.

WALTER S. EDGE, OF NEW YORK, N. Y.

AUTOMATIC FLOOD-GATE.

1,039,072.

Specification of Letters Patent. Patented Sept. 17, 1912.

Application filed November 3, 1911. Serial No. 658,341.

To all whom it may concern:

Be it known that I, WALTER S. EDGE, a citizen of the United States, and a resident of New York city, in the county of New York and State of New York, have invented certain new and useful Improvements in Automatic Flood-Gates, of which the following is a specification.

My invention relates to improvements in automatic flood gates and the object of my invention is to provide a gate which will hold the water at a predetermined level and when a slight rise above this level occurs, will quickly open and allow the flood to pass without allowing the water above the gate to rise more than a slight amount.

A further object of my invention is to provide a construction in which the gate can be easily removed without the necessity of dismembering any of its parts.

Referring to the drawings which form a part of this specification—Figure 1 is a perspective view of a construction embodying my invention in which the gate is shown in open position. Fig. 2 is a side elevation of the movable gate shown in its closed position in full lines and in its open position in dotted lines. Fig. 3 is a view of a portion of the gate showing a guide wall and part of the bearing on which the gate rocks. Fig. 4 is a cross sectional view through one side of one of the walls which support the gate. Fig. 5 is a plan view of the gate and side walls. Fig. 6 is a side view of one of the bearing elements carried by the gate. Fig. 7 is an edge view of the construction shown in Fig. 6. Fig. 8 is an edge view and Fig. 9 a side view of one of the bearing elements which is attached to one of the side walls and on which the gate rocks.

A, indicates the movable gate which is supported by two side walls B and C respectively. The said side walls are preferably supported on a concrete base D, the top surface of which is inclined at each side of the gate A as illustrated. The water flows between the walls in the direction indicated by the arrow E.

The walls B and C are preferably made of concrete material and are each provided with a guideway F, which extends from the top of the wall for a short distance and is then curved as illustrated at F'. The

curved portion of the guideway is provided with a metal lining G on its upper and lower sides. An abutment block H is fastened to each side wall with their faces in line with one edge of the guideway F as illustrated to support the gate when at rest in its vertical or closed position. A similar abutment H' is located below the point at which the gate rocks and disposed to align with the surface of the gate on the opposite side to the abutment H when the gate is in its vertical position. Carried by each side wall is a metal block I, which is provided with a curved surface I', and formed at each end of said curved surface are offsets I², and I³ respectively.

The gate is provided at each side near the top thereof with brackets J which carry short shafts on which the wheels J' rotate. These wheels J' enter the guideways G and serve to guide and support the gate A in its opening and closing movements.

Mounted on the gate at each side and below the middle thereof, is a rectangular shaped casting K which is provided with a projecting portion K' having a straight plane face. This face is adapted to contact with the curved surface forming the bearing I'.

The bottom end of the gate is beveled as illustrated at L to correspond with the inclined surface D'.

When the gate is in its closed position, the lower end of the projecting portion K' rests against the abutment I³ and when the gate is in its extreme open position, the opposite end of the portion K' abuts the abutment I². The curved guideway F is formed to permit the gate in its opening movement to rock smoothly on the bearing surface I', the wheels J' serving to hold the gate in proper position during its opening and closing movements, as will be readily understood. When the gate is in its extreme open position as illustrated by dotted lines in Fig. 2, one end thereof comes in contact with the abutments M, M, which are connected at each side of the gate to the side walls. Extending through each side wall is an air duct N which opens on the inner side of the walls at a point directly below where the upper end of the gate would rest in its extreme open position as indicated at O in

Fig. 2. The abutments H and H' contact with the gate when the gate is in its closed position and serve to prevent leakage past the gate.

6 The gate may or may not be constructed heavier below the point of the axis on which it rocks than above, as the water pressure controls entirely the operation of the gate regardless of its weight. Due to the construction of the bearing parts I' and K', the point of support of the gate constantly changes as the gate opens under control of the wheels, so that when the gate once starts to open or close, it will continue to 10 so move until fully opened or closed provided there is no decided change in the water level during the motion.

15 The operation of the gate depends upon the fact that the center of pressure of the total water pressure acting on a rectangular surface such as that presented by the gate is at two-thirds of the depth below the surface. The normal water level is carried at a predetermined distance below the top of the 20 gate, which distance depends upon a number of factors effecting the particular design. The distance from the water level to the pivotal point I' is $2n$ or twice the distance from the point I' to the bottom of the 25 gate. The gate is then about to open. A slight rise in the water level throws the gate out of balance by moving the center of pressure above the pivot point I' and the curved guideway is so designed that the gate rolling 30 upon it and guided and restrained by the wheels J' will continue to open with a steady motion until it is fully open. In this position the water will discharge both over and under the gate. The purpose of the air passage O is to admit air below the gate and 35 prevent the formation of a vacuum under the gate when the gate starts to close. As soon as the flood is past and the level of water above the gate is lowered, the gate 40 will at once close with a steady motion and will close tightly leaving the water level slightly below the normal water level above the gate.

45 It is obvious to those skilled in the art that the side walls and gate may be made of different materials depending on the conditions of the construction and the volume of water to be passed through the gate. In the present construction, I have illustrated the 50 side walls as being formed of concrete material and the gate is made of metal, but the gate might be made of wood and the side walls of wood or other suitable material.

55 The gate may be removed by lifting it 60 vertically, the wheels J' passing up through that portion of the guideway indicated by F and since there is nothing on the side wall to obstruct the gate in its upward movement, it may be removed in case repairs are 65 necessary.

Having thus described my invention, I claim as new:—

1. An automatic flood gate comprising two walls spaced apart from each other, each of which is provided with a curved guideway and a gate which extends from one wall to the other, means on which said gate may rock, and means co-operating with said guideways to hold said gate in proper position during its opening and closing 70 movements.

2. An automatic flood gate comprising two walls spaced apart from each other, each of which is provided with a curved guideway, a gate supported below its median center line on bearings carried by said walls, said gate being provided with guiding means 80 which enter said guideways in said walls.

3. An automatic flood gate comprising two walls spaced apart from each other, each of which is provided with a guideway which is open from the top to the bottom thereof and one portion of which is curved, a gate which extends from one wall to the other, means carried by said walls on which 85 said gate may rock, and means mounted on said gate and movable in said guideways to hold said gate in proper position during its opening and closing movements.

4. An automatic flood gate comprising two walls spaced apart from each other, each of which is provided with a curved guideway and a gate which extends from one wall to the other, curved bearings on which 90 said gate may rock, and means co-operating with said guideways to hold said gate in proper position during its opening and closing movements.

5. An automatic flood gate comprising two walls spaced apart from each other, each of which is provided with a curved guideway, a gate which extends from one wall to the other, curved bearings on which 95 said gate may rock, each of said bearings provided with an abutment at each end 100 thereof, and means co-operating with said guideways to hold said gate in proper position during its opening and closing movements.

6. An automatic flood gate comprising two walls spaced apart from each other, each of which is provided with a curved guideway, a gate which extends from one wall to the other and provided at each side 115 thereof with a projecting bearing portion, a curved bearing carried by each of said walls on which said projecting portion rocks, said gate carrying at each side thereof projecting means which enter said curved guideways to hold said gate in proper position 120 during its opening and closing movements.

7. An automatic flood gate comprising two walls spaced apart from each other, each of which is provided with a curved guideway, a gate which extends from one 130

wall to the other, wheels carried by said gate
near the top end thereof and entering said
guideways, curved bearings on which said
gate may rock, and means carried by said
walls to serve as abutments for said gate
when in its open position.

Signed at New York city in the county of

New York and State of New York this 2nd
day of November A. D. 1911.
